UNITED STATES PATENT OFFICE

2,324,503

ARMORED OBSERVATION UNIT

Arthur W. Herrington, Indianapolis, Ind., assignor to Marmon-Herrington Company, Inc., Indianapolis, Ind., a corporation of Indiana

Application January 9, 1942, Serial No. 426,152

2 Claims. (Cl. 109—58.5)

The object of my invention is to produce an observation unit, particularly designed for armored vehicles, by means of which the eyes of the user may be protected against bullets and other flying objects, the construction being such that the amount of afforded protection may be readily varied according to probable dangers and such that the transparent element may be readily removed and replaced.

The accompanying drawings illustrate my invention.

Fig. 1 is a vertical medial section of an embodiment of my invention;

Fig. 2 a section on line 2—2 of Fig. 3;

Fig. 3 a front elevation with the protector plate in battle position;

Fig. 4 a rear elevation with the protector plate in non-battle position;

Fig. 5 a perspective view on a smaller scale of the transparent element;

Fig. 6 a perspective view, on the scale of Fig. 5, of the removable wedge; and

Fig. 7 an elevation of a modified form.

In the drawings 10 indicates the main frame, conveniently defining a rectangular opening and provided with an internal flange 11 and an external flange 12 by means of which the structure may be attached to an apertured body plate 13 of an armored vehicle.

At the front of the main frame, at opposite sides of the aperture defined by flange 11, are lugs or ribs 14 the opposed faces of which are grooved as indicated at 15, 15.

Fitting grooves 15, 15 and extending there-between across the aperture defined by flange 11, is a protector plate 16 provided with a sight-slit 17. Plate 16 is carried by the rock shaft 18 which is journalled in one side of frame 10 and provided, at its inner end, with an operating means, illustrated here as a crank 19.

That portion of frame 10 to the rear of flange 11 forms a pocket for a transparent bullet-proof unit 20 which is conveniently formed by cementing together several thicknesses of so-called bullet-resistant glass, as indicated in Fig. 5. A cushioning gasket 21 is interposed between unit 20 and flange 11.

In order to retain unit 20 in frame 10 and, at the same time, facilitate removal and replacement, I provide the key-frame 22 which is wedge-shaped in vertical cross section and defines an aperture about the same size as, and alignable with, the aperture defined by flange 11. One face of the key-frame 22 engages the rear face of unit 20 and the inclined rear face of the key-frame at

its opposite vertical sides engages cam blocks 23, 23 attached to the rear face of frame 10.

The key-frame is held in place by a swinging latch finger 24 pivoted on stud 25 carried by frame 10 and conveniently made of spring metal so as to be capable of exerting a spring pressure upwardly on the key-frame.

In Fig. 7 the key-frame carries on its lower edge spring fingers 30, 30 the free outer ends of which separably engage spring latches 31, 31, attached to the opposite vertical sides of main frame 10.

The upper and lower sides of frame 10 at their rear edges are notched, as indicated at 26, Fig. 2, so that the thumb and finger of the operator may more readily grasp unit 20 for removal and replacement.

A spacer 27 provides an abutment for plate 16 at its closed, or combat, position.

During combat, in order to reduce to a minimum the chance of unit 20 being shattered by a direct hit through the aperture defined by flange 11, shutter 16 is readily swung to the position shown in Fig. 1 by manipulating crank 19.

During non-combat periods, shutter 16 will be swung to a position to one side of unit 20, as indicated by dotted lines in Fig. 4, so that the user may have a greater vertical range of vision.

In case of shattering of unit 20 the operator, by swinging latch 24, may readily withdraw key-frame 22, whereupon the damaged unit 20 may be extracted and a new unit quickly substituted and locked in place.

While my device has been primarily designed to be placed for use by the driver of an armored vehicle, it will be understood that it may be useful in other environments.

I claim as my invention:

1. An armored observation unit comprising, a main body frame defining an aperture, inwardly-projecting means intermediate the length of said aperture forming a seat for a transparent unit insertable in said aperture, said transparent unit seatable within the inner end of the frame aperture, an apertured protector plate seated in said frame adjacent the outer end of said frame aperture, means accessible at the inner end of said frame aperture by which said protector may be moved to and from position blocking the outer end of said frame aperture, and movable means accessible at the inner end of said frame aperture for retaining the transparent unit in place.

2. An armored observation unit comprising, a main body frame defining an aperture and provided with an inwardly-projecting flange adjacent

the outer end of said aperture, a transparent unit fitting said aperture and seated on said flange, an aperture wedge-shaped key-frame engageable with the inner end of said transparent unit, cam flanges carried by the main body adjacent the inner end thereof and forming an abutment for said key-frame, movable means mounted on the main body accessible adjacent the inner end of the main body and engageable with the key-frame

to hold it in place, slots in the main body flanking the outer end of said aperture, an apertured protector-plate movably mounted in said slots, and a rock shaft journaled in the main body and carrying said shutter with the inner end of said shaft accessible adjacent the inner end of the main body.

ARTHUR W. HERRINGTON.
